CLAIM

The ornamental design for an ice cream packaging, as shown and described.

DESCRIPTION

FIG. 1 is a perspective view of the ice cream packaging showing our new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof; and,

FIG. 8 is a perspective view of a second embodiment showing our new design, but for the number of sections, the second embodiment being similar to the first embodiment.

1 Claim, 7 Drawing Sheets
